UNITED STATES PATENT OFFICE.

JOHN L. ARMSTRONG, OF CHICAGO, ILLINOIS, ASSIGNOR TO THE NATIONAL LOCK WASHER COMPANY, OF NEWARK, NEW JERSEY, A CORPORATION OF NEW JERSEY.

COMBINED SASH HOLDER AND WINDOW RELEASE.

Application filed June 7, 1926. Serial No. 114,240.

This invention relates to a combined sash holder and window release of the character shown and described in my Letters Patent No. 1,547,775, issued July 28, 1925.

6 In this patented construction a stationary lever extended from the side of the sash holder casing at the top, while a pivoted lever projected from the casing below the stationary lever, and by forcing the pivoted lever upward the desired result was effected.

10 The present invention accomplishes the same result by a downward thrust of the pivoted lever and will be best understood from the following description, reference being had to the accompanying drawings in which

15 Figure 1 is an inside elevation showing an ordinary sash holder equipped with one form of my improvement with the parts in normal position—

Figure 2 is a view similar to Figure 1 but showing the pivoted lever operated to release the sash—

20 Figure 3 is a view similar to Figure 1 but showing a modified form of the invention—

Figure 4 is an elevation similar to Figure 3 but showing the position of parts after the pivoted lever has been operated to release the window—

25 Figure 5 is a view similar to Figure 1 but showing the stationary lever extending from the bottom portion of the casing instead of from the top, and

30 Figure 6 is a view similar to Figure 5 but showing the positions assumed by the parts after the pivoted lever has been operated to release the window.

35 In the description to follow similar numerals of reference will be used to designate similar parts in the several figures of the drawing.

40 Referring to Figures 1 and 2, 1 denotes the casing of the sash holder provided with the usual dowels 2 to extend within the sash. 45 3 is an L-shaped sash holder lever, herein-after called the operating member, pivoted to a post 4 extending from the casing, and 5 is a coil spring interposed between the inner end 6 of the member 3 and the casing, where- 50 by the action of the operating member will be resilient.

55 In the upper part of the casing is a guided bolt 7 having in its lower edge a recess 8 within which engages a toe 9 that extends

from the upper edge of the inner end 6 of the operating member 3.

In Figure 1 this bolt is shown projected for latching engagement with the usual rack at the side of the window casing, and the spring 5 acts against the operating member 60 to normally effect this and to swing the outer lever 10 extending from said member upward as shown, and it will therefore be clear that when this lever 10 is forced downwardly the toe 9 will operate within the recess 8 65 to throw the bolt 7 inwardly to retract it from said rack.

70 Slidably guided within the bottom of the casing is a vertically disposed independent plunger pin 11, which moves freely through a boss 12 preferably formed on the casing, to contract the sill denoted by 13.

75 This plunger 11 is a pin or short bolt and is provided with a head 14 whose upper surface is spherical as shown.

80 The operating member 3 has at some suitable location along its lower edge portion a suitably formed surface, which, when said member is forced downwardly, contacts the head 14 and drives the pin 11 against the sill 13, and, as it is advisable to exert considerable force against this head, a cam shaped member 15 is formed integral with the lower edge portion of the part 6, and the pin 11 is located in nearly the same vertical plane with the post 4, so that, when the lever 10 is forced downwardly, this cam 15 will exert great force against the head 14, owing to the very considerable leverage in favor of the operator, and this will both retract the latching member 7 and will also raise the sash from the sill, as shown at Figure 2. By easy manipulation, the lever 10 is held in its depressed position and force exerted against the stationary lever 16 to raise the sash.

85 This lever 16, in substantially all sash holders, extends rigidly from the side of the upper part of the casing, and in Figures 1 and 2, this invention is shown adapted to operate in connection with a stationary lever positioned in this manner.

90 But attention will presently be called to a more convenient adaptation of the invention necessitating, however, a special location of this stationary lever.

95 In the constructions heretofore described, the latching member consisted of a sliding bolt, but this invention is adapted to operate

equally as well with a pivoted latching member, and therefore, referring especially to Figures 3 and 4, there is illustrated a latching member 17 that is pivoted around the 5 post 18 extending from the casing one end of said member adapted to be swung into latching engagement with the usual rack on the window casing, while the other extremity is formed with a recessed portion 19 within 10 which operates a toe 20 extending from the upper portion of the inner end 6 of the operating member, and a coil spring 21 extends between this end of the member 17 and the top portion of the casing, which spring, like 15 that heretofore described, serves to restore all the parts to normal position with the member 17 in latching engagement with said side rack.

The operation of this construction shown 20 at Figures 3 and 4 is precisely the same as that heretofore described with respect to the structures shown at Figures 1 and 2.

Referring particularly to Figures 5 and 6 the constructions therein shown are the same 25 as those shown at Figures 1 and 2, with the sole exception that a lever 22 extends rigidly from the lower portion of the casing instead of from the top portion; so that the operator may grasp both levers in his hand, and by a 30 squeezing action, and also the exertion of a downward force, bring the parts into the position shown at Figure 6, with the latch-

ing member retracted and the sash raised from the sill, so that it is then merely necessary to exert a lifting effort to raise the sash 35 as far as may be desired.

The invention is therefore not limited to any particular latching member or to any specified location of the rigid lever.

What is claimed is:—

A combined sash holder and window release, comprising a casing having a stationary lever extending therefrom, an operating member pivoted within said casing and having a lever extending therefrom in juxtaposition with respect to the stationary lever, a separate latching member movable in the casing, connections between said latching and operating members whereby the downward and upward swinging of the operating member lever will effect the unlatching and latching movements of the latching member, a spring which acts to effect the latching movement and to restore the parts to normal positions, a vertically disposed independent plunger pin slidably guided within the bottom of the casing and adapted to be forced downwardly by the bottom portion of the operating member with a camming action when the latter is forced downwardly to effect the withdrawal of the latch member.

In testimony whereof I affix my signature hereto.

JOHN L. ARMSTRONG.
